UNITED STATES PATENT OFFICE.

DAVID A. CHILDS, OF COLUMBIA, SOUTH CAROLINA.

KEY-OPERATING DEVICE.

SPECIFICATION forming part of Letters Patent No. 358,649, dated March 1, 1887.

Application filed October 18, 1886. Serial No. 216,569. (No model.)

To all whom it may concern:

Be it known that I, DAVID AUGUSTUS CHILDS, of Columbia, in the county of Rich-
land and State of South Carolina, have invented
5 a new and Improved Turning Attachment for
Door-Keys, of which the following is a speci-
fication, reference being had to the annexed
drawings, forming a part thereof, in which—

Figure 1 is a perspective view showing the
10 application of my improvement. Fig. 2 is a
side elevation of a key to which my attachment
has been applied, and Fig. 3 is a side elevation
of the attachment.

Similar letters of reference indicate corre-
15 sponding parts in all the views.

The object of my invention is to provide a
simple and effective device for operating the
keys of doors from a distance.

My invention consists in a split pulley adapt-
20 ed to be clamped upon the shank of a door-
key, and grooved in its periphery to receive a
cord extending over one or more pulleys to a
distant point, the cord being partly wrapped
around the split pulley on the key, so that
25 when it is pulled it will turn the key and lock
or unlock the door, according as the cord is
wound in one direction or the other upon the
split pulley.

The key A, which may be of any well-known
30 form, carries upon its shank *a* a grooved pul-
ley, B. This grooved pulley may be formed
integrally with the key; but I prefer to apply
to the key a split pulley, like that shown in
Fig. 3, each half of the pulley being provided
35 with ears *b* at the adjoining edges of the halves
of the pulley, for receiving the screws *c*, by

which the halves of the pulley are firmly
clamped upon the shank *a* of the key.

To the casing C of the door, at the hinged
side thereof, is secured a pulley, *d*, and to the 40
pulley B on the key A is secured a cord, D,
which is wrapped partly around the said pul-
ley B and extends around the pulley *d*, thence
around the pulleys *e,f,g* to a distant part of the
room in which the door opens, or to an ad- 45
joining room, as circumstances may require.

When it is desired to unlock the door, the
pulling of the cord D revolves the pulley *d*
and turns the key in the lock, so as to either
withdraw or project the bolt, according as the 50
cord is wound around the pulley in one direc-
tion or the other, to lock or unlock the door.

I am aware that a pulley has been secured
to a knob shank or spindle, so that a door may
be opened by means of a cord and pulleys from 55
a distance, and I therefore do not claim such
invention.

Having thus fully described my invention, I
claim as new and desire to secure by Letters
Patent—

1. As an improved article of manufacture,
a key provided with a pulley on its shank, as
set forth.
2. The combination, with the key A, of the
sectional pulley B, each section being provided 65
with apertured ears *b* at the adjoining edges,
and the screws *c*, substantially as herein shown
and described, and for the purpose specified.

D. A. CHILDS.
